NILS GUNNAR PALMGREN, OF STOCKHOLM, SWEDEN, ASSIGNOR TO TELEFON AKTIE-BOLAGET L. M. ERICSSON, OF STOCKHOLM, SWEDEN, A COMPANY OF SWEDEN

SELECTOR TESTING CIRCUIT

Application filed March 29, 1929, Serial No. 351,052, and in Sweden March 24, 1928.

In automatic telephone exchanges incorrect connections sometimes are caused by the fact that a selector hunting for a free junction line is passing over the contacts of a junction line in the moment of interruption of a previously completed talking connection over said junction line. Such incorrect connections have a tendency to occur especially in such systems in which the restoration is initiated by the interruption of a circuit over the private wiper of the selector and the third wire. A selector passing over the contact appertaining to a junction line included in a talking connection in the moment of interruption may namely then prevent the interruption of said circuit as the latter instead is closed over the private wiper of said selector and the appertaining testing relay, the hunting selector being thus stopped and the restoration of the succeeding selectors in the talking connection prevented. The object of the present invention is to eliminate incorrect connections of said kind and consists substantially therein that the resistance in that portion of the testing circuit in question which belongs to a free junction line, after completed testing and connection into circuit, will be increased to a value which per se is sufficient to prevent the connection of another selector to the already engaged junction line independent of the changes which afterwards may occur in other parts of the testing circuit by way of example upon interruption of the talking connection.

The invention will be more closely described with reference to the accompanying drawing showing a circuit diagram for two group selectors GV_1 , GV_2 only those circuits being then shown which are required to explain the invention.

The selectors may be of any arbitrary design. In the shown example it is assumed that they are of that type in which they are set under the control of registers. The selectors are assumed to have two setting motions in the same plane i. e. a rotating motion to select a certain contact row and also a radial motion to select a line within the contact row. It is further assumed that the selectors are of that type in which the appertaining contact bank consists of bare wires a , b , c which

extend perpendicularly to the plane of motion of the contact arms through a plurality of selectors. During their rotating motion the contact arms move outside the wire bank and during the succeeding radial motion they move into the space between the wires a , b , on the one side, and the wire c , on the other side. The selectors are power driven in known manner under the control of two clutch magnets MHG and MVG and two control magnets CVG and CRG the turning motion being then produced by a simultaneous energization of the magnets MHG and CVG whereas the radial motion is effected by a simultaneous energization of the magnet MHG and CRG. At the restoration, the clutch magnet MVG co-operates in a similar manner with a magnet CRG and CVG. The group selectors are further provided with throw-over switches VO and RO the former of which is shifted when the selector leaves its normal position and is returned to the position shown on the drawing upon the restoration of the selector whereas the latter is shifted when the contact arm begins its radial movement and is returned to the position shown on the drawing upon the return to the starting position of the radial motion.

The connection to a calling subscriber's line can be brought about in a manner known per se by means of a call finder AS of substantially the same design as the group selectors.

The system functions substantially as follows. After the calling subscriber's line has been connected to a junction line FL_1 through the call finder AS a free register RR is connected in known manner through a finder RS to the junction line. The register is only shown diagrammatically as its function does not need to be described in detail in this connection. A sequence switch not shown on the drawing and appertaining to the junction line FL_1 in this moment closes a circuit 1 over a contact k in said sequence switch through a relay R_0G_3 and two ohmic resistances R_1 and R_2 . After the register is set according to the desired number a circuit 2 is closed through a relay R_1G_2 which locks itself over the contact 3 and at the same time closes a circuit 4 through a relay R_1G_1 .

of high resistance. When the latter relay is energized it locks itself over its contact 5 and closes also a circuit 6 through the control magnet CVG which in turn closes a circuit 7 through the clutch magnet MHG. Thereby the selector is started. During the following rotating motion of the selector impulses are sent in known manner over a circuit 8 to the register RR a register switch being thereby set in known manner. When this register switch reaches a certain setting position the circuit 2 is interrupted the relay R_1G_2 being then de-energized. The latter relay interrupts the circuit 8 and opens the contact 9 in the circuit 6, the control magnet CVG and, as a consequence, also the clutch magnet MHG being then de-energized so that the selector is stopped. Then a circuit 10 is closed through the control magnet CRG which in turn closes the circuit 11 through the clutch magnet MHG. As a consequence, the selector is started in radial direction to hunt for a free junction line in the selected contact row. When the contact arms make contact with a free junction line FL_2 a testing circuit 12 is closed over the testing contact c and through the non-inductive resistances R_3 , R_4 corresponding to the resistances R_1 , R_2 . The testing circuit contains a testing relay R_1G_3 which is now energized, the circuit 10 of the clutch magnet CRV being then interrupted which results in that the selector stops. At the same time a circuit 13 is closed through a relay R_1G_4 and the control magnet CVG. The relay R_1G_4 has such a high resistance that the control magnet CVG then remains inoperative. On the other hand, the relay R_1G_4 is energized then locking itself over the contact 14. The relay R_1G_4 at its contact 15 further short-circuits the winding GL of the testing relay R_1G_3 the current in the testing circuit being then amplified to such a degree that the junction line FL_2 is marked as engaged through the drop of voltage thus created at the testing contact c .

The winding GL is so wound that it counteracts the other winding HL of the testing relay. The object of this arrangement is to render the testing relay comparatively insensitive in the movement of testing in order to prevent a double connection in such cases when two group selectors simultaneously make contact with the same junction line as the current then on account of the parallel connection of two testing relays to the same testing contact c becomes insufficient to start operation of any of the testing relays. By the short-circuiting of a counteracting winding both a reduction of the resistance in the testing circuit and a large increase of the operative number of ampere-turns of the testing relay is gained which is important considering the other functions of the testing relay as will be further described in the fol-

lowing. By way of example, it may be mentioned that a satisfactory operation of the relay is obtained by providing HL with about 6,000 turns and the winding GL with 1,500 counteracting turns. The resistance R_3 may then be about 250 ohms and the resistance R_4 about 150 ohms.

After the completed connection to the junction line FL_2 a circuit 16 is closed in the register RR through a relay R_2G_2 in the group selector GV_2 . Said relay is energized and locks itself over its contact 17 and starts similar connections as the relay R_1G_2 . A relay R_2G_1 of a high resistance and corresponding to the relay R_1G_1 is thus connected into circuit over a contact 18 of the relay R_2G_2 the relay R_2G_1 then being energized and locking itself over its contact 19. At the same time a circuit 20 is closed through a control magnet CVG which in turn closes a circuit 21 through the clutch magnet MHG. The group selector GV_2 thus starts its rotating motion current impulses being then sent over the circuit 22 to the register. When the corresponding register switch has been set in a previously marked position the circuit 16 for the relay R_2G_2 is interrupted the selector being then stopped. A circuit 23 is then closed through the control magnet CRG and also a circuit 24 through the clutch magnet MHS whereby the selector is started in its radial motion to hunt for a free junction line FL_3 . When the group selector finds such a line a current path 25 is closed through the testing relay R_2G_3 which is energized and stops the selector at the same time as it closes a circuit 16 for the relay R_2G_4 . The latter relay locks itself over its contact 27 and short-circuits at the same time over its contact 28 the winding GL of the relay R_2G_3 . The relays R_2G_3 and R_1G_3 are identical and serve the same purpose. The winding GL counteracts thus the winding HL and the short-circuiting of the winding GL marks the junction line FL_3 as engaged. The completion of the connection may then be performed in any arbitrary manner.

When the relay R_2G_1 was energized it disconnected the branch wire including the resistance R_4 in the testing circuit which now instead is held closed over the relay R_2G_1 . As the latter relay has a comparatively high resistance, by way of example 550 ohms, the short circuit of the winding GL of the testing relay R_1G_3 is then without any essential importance for the marking of the junction line FL_2 as engaged but the resistance in the winding of the relay R_2G_1 together with the resistance R_3 is per se sufficient to prevent a hunting selector to connect itself to said junction line.

When the calling subscriber answers a contact 29 is closed in any known manner whereby the testing relay R_2G_3 is short-circuited. When the latter relay, as a consequence, is de-

energized the testing contact *c* is connected to the positive pole of the battery over a contact 30 in R_2G_3 and a contact 31 in R_2G_4 . As the resistance R_3 is comparatively small the testing relay R_1G_3 in the group selector GV_1 is thereby practically shortcircuited, which results in that the relay R_0G_3 is shortcircuited in similar manner over the corresponding contacts 32 and 33. The relay R_0G_3 then sends a current impulse to the call meter. Said short-circuits remain for such a period of time as is required to transmit the call meter impulse. When the contact 29 is then reopened the testing relays R_2G_3 and R_1G_3 are again energized. Thanks to the short-circuiting of the winding GL the testing relays are now supplied with a sufficient current to be actuated in series with the relay R_2G_1 having a high ohmic resistance or a corresponding relay R_3G_1 in the selector appertaining to the junction line FL_3 , respectively.

When the subscriber again hooks up the receiver after a finished call, initially, the group selector G_1 is restored and then the successive selectors in turn. The restoration is started by that the contact *k* is interrupted the relay R_1G_1 then being de-energized and closing a circuit 34 through the control magnet net CRG which in turn closes a circuit 35 through the clutch magnet MVG. This results in that the selector is now restored in radial direction. When the contact arms reach the starting position for the radial motion the switch RG_1 is actuated the circuit for the control magnet CRG being then interrupted and the selector stops. At the same time, however, a circuit 36 is closed through the control magnet CVG which in turn closes a circuit 37 through the clutch magnet MVG the selector being thereby restored to the starting position in which the switch VO_1 is actuated so as to interrupt the circuit of the control magnet CVG and the selector stops.

When the relay R_1G_1 was de-energized the circuit of the relay R_1G_4 was interrupted and also the circuit over the third wire at the contact 38 of the relay R_1G_1 . When the testing relay R_1G_3 is deenergized the group selector GV_1 is prepared to make a new connection. Upon the interruption of the circuit of the third wire also the relay R_2G_1 is de-energized which relay is establishing similar connections at the group selector GV_2 as has been just described regarding the group selector GV_1 . By said connections also the group selector GV_2 is now restored.

If in that moment when the circuit 12 was interrupted at the contact 38, another group selector GV_1 during the hunting for a free junction line should pass the contacts appertaining to the junction line FL_2 it is conceivable that the relay R_2G_1 is not de-energized because it should then be supplied over the testing magnet R_1G_3 in said selector said

relay then being able to attract its armature and thus connects the selector to the junction line FL_2 . Such an incorrect connection is, however, avoided, thereby that the relay R_2G_1 has such a high resistance that the testing relay R_1G_3 in the hunting selector is unable to attract its armature. Also the fact that the windings HL and GL in this moment are connected in series the testing relay thus having a comparatively high resistance concurs to the same result. Thanks to the series connection of the windings HL and GL the resistance of the testing relay is so high that it also prevents the relay R_2G_1 to remain energized while the hunting selector is still engaging the contacts in question. The latter relay thus drops its armature in the same moment as the circuit of the third wire is interrupted at the contact 38. During the restoration of the selector GV_2 also the branch wire containing the resistance R_4 is interrupted at the contact 40, 41 of the switches VO_2 and RO_2 . The testing contact *c* thus remains tensionless until the selector is completely restored. One is thus completely sure of that the restoration is not in any way disturbed by the operation of a selector which in the moment of connection is passing over the contacts of a junction line included in a talking connection.

I claim:

1. In a telephone exchange system, a test circuit arrangement for selectors comprising a number of selectors, a number of junction lines, accessible to said selectors, a test circuit for each of said selectors extending over a movable contact of the selector, a test relay included in the selector section of said circuit, means under the control of said relay for reducing the resistance of said part of the test circuit upon seizure of an idle junction so as to provide a busy test potential for said junction, a test guard resistance, and means associated with the junction line and arranged to operate upon the seizure of the junction by a selector to connect said test guard resistance into the junction section of the test circuit to increase the resistance of the junction section of the test circuit so as to guard the junction after removal of said busy test potential.

2. In a telephone exchange system, a test circuit arrangement for selectors comprising a number of selectors, a number of junction lines, accessible to said selectors, a test circuit for each of said selectors extending over a movable contact of the selector, a test relay included in the selector section of said circuit, means under the control of said relay for reducing the resistance of said part of the test circuit upon seizure of an idle junction so as to provide a busy test potential for said junction, two branch circuits forming parallel branches of the junction section of the test circuit, one of said branches including

an off-normal contact of a selector associated with the junction line, a low resistance in the branch last mentioned, a high test guard resistance in the other of said branches, and means associated with the junction line and arranged to operate upon the seizure of the junction line by a selector to connect said test guard resistance into circuit instead of said low resistance.

- 10 3. In a telephone exchange system, a test circuit arrangement for selectors comprising a number of selectors, a number of junction lines, accessible to said selectors, a test circuit for each of said selectors extending over a movable contact of the selector, a test relay included in the selector section of said circuit, means under the control of said relay for reducing the resistance of said part of the test circuit upon seizure of an idle junction so as to provide a busy test potential for said junction, two branch circuits forming parallel branches of the junction section of the test circuit, one of said branches including an off-normal contact of a selector associated with the junction line, a low resistance in the branch last mentioned, a high test guard resistance in the other of said branches forming the winding of a relay, means associated with the junction line and arranged to operate upon the seizure of the junction line by a selector to connect said test guard resistance into circuit instead of said low resistance, and a front contact on said relay included in the test circuit so as to disconnect battery potential from the test circuit upon the de-energization of said relay.
- 15 4. In telephone exchange system, a test circuit arrangement for selectors comprising a number of selectors, a number of junction lines, accessible to said selectors, a test circuit for each of said selectors extending over a movable contact of the selector, a test relay included in the selector section of said circuit and having two counteracting windings, means under the control of said relay for shortcircuiting one of said windings thereby reducing the selector of the test circuit so as to provide busy test potential for said junction, a test guard resistance, and means associated with the junction line and arranged to operate upon the seizure of the junction by a selector to connect said test guard resistance into the junction section of the test circuit to increase the resistance of the junction section of the test circuit so as to guard the junction after removal of said busy test potential.

In testimony whereof I affix my signature.
NILS GUNNAR PALMGREN.
